CLAIM

The ornamental design for a control panel for a copier or the like, as shown and described.

DESCRIPTION

FIG. 1 is a top plan view of a control panel for a copier or the like showing our new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view of the control panel for a copier or the like (with cover open) of our new design;

FIG. 7 is a front elevational view of the control panel for a copier or the like as shown in FIG. 6;

FIG. 8 is a back elevational view of the control panel for a copier or the like as shown in FIG. 6;

FIG. 9 is a left side elevational view of the control panel for a copier or the like as shown in FIG. 6; and

FIG. 10 is a right side elevational view of the control panel for a copier or the like as shown in FIG. 6.
